UNITED STATES PATENT OFFICE.

JOHN WALTER DRAKE, OF DETROIT, MICHIGAN, ASSIGNOR TO HUPP MOTOR CAR COMPANY, OF DETROIT, MICHIGAN, A CORPORATION OF MICHIGAN.

DESIGN FOR A VEHICLE HUB-CAP.

47,070.

Specification for Design.

Patented Mar. 9, 1915.

Application filed October 22, 1914. Serial No. 868,136. Term of patent 14 years.

To all whom it may concern:

Be it known that I, JOHN WALTER DRAKE, a citizen of the United States of America, residing at Detroit, in the county of Wayne and State of Michigan, have invented a certain new, original, and ornamental Design for Vehicle Hub-Caps, of which the following is a specification, reference being had therein to the accompanying drawings, forming part thereof, in which—

Figure 1 is a perspective view of a vehicle hub cap, showing my new design; and Fig. 2 is a side elevation thereof.

I claim:

The ornamental design for a vehicle hub cap, as shown.

JOHN WALTER DRAKE.

Witnesses:

CALVIN H. DUNLAP,
ROSE WEINSTEIN.
